ABSTRACT

Bag handling equipment including novel electrically controlled hydraulic means to engage firmly with the flaps on the lead bag of a supply of bags advancing in a horizontal plane and effective to carry the engaged bag from its initial vertical position into a substantially horizontal position for delivery into associated bag handling or treating apparatus.

BAG HANDLING EQUIPMENT

The invention relates to improvements in bag handling equipment and is more specifically concerned with novel structure and apparatus operable automatically to feed bags from a supply thereof individually to associated apparatus such as, for example, a printing machine.

More particularly, the disclosed apparatus includes incrementally actuated conveyor means operable to advance a supply of bags, arranged thereon in upstanding substantially vertical position, toward bag feeding mechanism associated therewith. The bag feeding mechanism is of a type wherein means movable through a vertical arc functions to initially carry novel bag grabber means into engagement with the lead bag, which grabber means is then actuated to positively engage the bag and then carry same upwardly and away from the supply into a substantially horizontal position for feeding into a related apparatus or for otherwise dispensing of same.

The means movable in a vertical plane and the bag engaging means carried thereby, preferably are hydraulically actuated in response to actuation of select switches in an associated electrical control circuit.

It is therefore an object of the invention to provide bag handling equipment of the character referred to.

Another object is to provide novel means and mechanism for engaging or grabbing a bag and carrying it into a position for advance into associated apparatus.

Another object is to provide means, in equipment of the character referred to, for advancing step-by-step a supply of bags arranged in a vertical plane.

Another object is to provide novel means to engage a flap or flaps on a bag to be advanced and to retain such engagement until the bag is carried to a predetermined position.

Another object is to provide novel electrically controlled hydraulic means for operating the various components of the bag handling equipment.

Another object is to provide bag handling equipment of the character referred to which is not difficult to construct or maintain serviceable, and which is very efficient in use.

Other objects and advantages of the invention will become apparent with reference to the following description and accompanying drawings.

In the drawings:

FIG. 1 is a side elevational view of the bag handling equipment showing the conveyor means partially broken away.

FIG. 2 is a top plan view of the bag engaging or grabbing mechanism, showing it in non-engaging position.

FIG. 3 is a view similar to FIG. 2, showing the mechanism engaged with a bag.

FIG. 4 is a perspective view of a representative bag.

FIG. 5 is an elevational view of the hydraulic system and electrical controls therefor, viewed from the side of the equipment opposed to the side shown in FIG. 1.

FIG. 6 is a schematic view of the hydraulic system.

FIG. 7 is a schematic view of the electrical wiring of the system.

FIG. 8 is a side elevational view of a modified form of bag handling equipment.

FIG. 9 is an elevational view of a bag of the type handled by the FIG. 8 equipment.

Referring to the exemplary embodiment of the invention, shown in FIGS. 1 through 7, and particularly to FIG. 1, the bag handling equipment is embodied in a horizontal frame structure 11, mounting a bag feed endless conveyor 12. The conveyor is trained, at the feed end of the frame, over sprockets 13 mounted firmly on a horizontal shaft 14, and its other end is trained over a conventional idler sprocket assembly, not shown. The shaft 14 carries on one end a ratchet type drive element 15 including a radially extending actuating arm 16 having its free end pivotally connected to the end of a piston rod 17 extending from a hydraulic piston-cylinder assembly 18 which is mounted at its rear end, pivotally, to an upstanding rigid member 19 formed integral with the frame structure 11.

The bag conveyor 12 mounts a plurality of mutually spaced apart uprights 21 between which stacks of bags 22 are arranged in a vertical position. In use, the bags are advanced toward the feed mechanism, to be described presently, in incremental steps responsive to intermittent operation of the piston-cylinder assembly 18. As best shown in FIG. 4, each bag 22 has an infolded flap 22a on each of its vertical margins and the bags are arranged on the conveyor 12 with the side bearing the flaps 22a facing toward the feed mechanism.

Also mounted pivotally on the frame structure 11, in advance of the delivery end of the conveyor 12, is a bag feeding mechanism embodying a vertically disposed frame assembly 23 comprised of a pair of laterally spaced apart vertical arms 23a firmly connected, at their upper ends, by a cross bar 24. It should be noted that the upper end of this frame assembly terminates in a plane substantially midway between the top and bottom edges of the bags 22 and it is adapted to be reciprocably rocked about its pivot 25 toward and away from the bags 22. For this purpose, an hydraulic piston-cylinder assembly 26 is provided, the body or cylinder thereof being connected, as at 27, to the frame 11 and its piston rod 28 connected to the frame assembly 23, as at 29. When operated, the frame assembly moves between the full line position shown in FIG. 1, and the dotted line position there illustrated.

The frame assembly 23 carries on its upper end an hydraulically actuated bag engaging or gripper assembly generally shown at 31.

As best shown in FIGS. 1-3, the bag grabber or gripper assembly 31 is mounted on the upper extremity of the frame assembly 23, for pivotal swinging in a vertical plane; i.e.: from the rearwardly tilted full line position shown in FIG. 1 into the forwardly tilted dotted line position therein shown. The gripper assembly is carried on a horizontal bar 32, pivoted at 33 to the cross bar 24. End extensions 34 are firmly connected one to each end of the bar 32 and each has a curved end portion 35 adapted, when the assembly is carried into contact with the lead bag 22, to cause the vertical side margins of the lead bag to be urged rearwardly, as shown in FIG. 3, so as to open up the bag flaps 22a on its vertical edges.

When the bag gripper assembly 31 is in its bag engaging position (FIG. 3) hydraulic means is actuated to cause the fingers 36 on a pair of flap engaging pawls 37 to engage behind the respective flaps 22a. These pawls 37 are pivotally mounted at 38 on a rearwardly pro-

jecting extension 39 of the horizontal bar 32, and normally lie in a retracted position as shown in FIG. 2. The hydraulic means for moving the flap engaging pawls from their FIG. 2 retracted position into their FIG. 3 extended position and vice versa, preferably comprises a pair of hydraulic piston-cylinder assemblies 40, one for each pawl, that are also carried pivotally by the horizontal bar 32.

It should be evident, that during one cycle of operation, the frame assembly 23 is carried forward from its full line position (FIG. 1) into the dotted line position shown. When in its retracted full line position the bag gripper assembly 31 is tilted rearwardly downwardly. When in its forward or advanced position (dotted lines) the bag gripper assembly 31 is tilted forwardly downwardly as shown. It is when in this position that the lead bag is contacted (FIG. 3) and the piston-cylinder assemblies 40 are actuated to engage the gripper fingers 36 behind the bag flaps 22a. The means provided to rock the bag gripper assembly 31 comprises a rigid link or rod 41 (FIG. 1) connected at one end, as at 42, to the bag gripper assembly 31, and at its other or lower end to a fixed pivot 43 on the main frame structure 11. Thus it will be seen that the lead bag 22 is carried from its substantially vertical position upwardly and forwardly into a substantially horizontal position to enable it to be engaged by feed means (not shown) on related equipment such as for example, a printing machine.

The hydraulic system is best illustrated schematically, in FIG. 6/ As there shown, fluid under pressure from any suitable source is delivered through a line 44 to a filter and mixer 45 from where it is delivered, when the proper valves therein are opened selectively, to either end of the piston-cylinder assembly 26 controlling operation of the grabber frame arm 23. A line 46 also leads from the feed line 44 to each of a pair of solenoid valves 47-48. A line 49 leads from solenoid valve 47 including a pair of flow regulators 51, to the chain drive piston-cylinder assembly 18 which operates in timed sequence. Similarly, a line 52, which also includes a pair of flow regulators 53, leads from the solenoid valve 48 to each of the piston-cylinder assemblies 40 controlling operation of the grabber fingers 36.

The electrical circuit is best shown in FIG. 7 and will be described in conjunction with a resume of operation. Electrical current is feed into the system through lines 54-55, on on-off switch 56 being provided in line 54. Line 54 is connected through line 57 directly with one terminal of solenoid valve 47 connected to the chain drive piston 18, the other terminal of which is connected by line 58 to an adjustable timer 59 which is energized through a line 61 having a micro-switch 62 therein.

As connected, when the switch 62, which is a safety switch, is closed, bags continue to advance with the conveyor for removal by coordinated operation of the bag frame assembly 23. However, should the frame assembly 23 be not functioning for any reason, the advance of bags along the conveyor 12 will carry the lead bag into contact with and open the switch 62 so as to stop the advance of bags.

The line 55 also is connected, through line 55a, to a pair of micro-switches 63-64. With the switch 63 closed, the frame assembly 23 is spaced from the bags (full lines in FIG. 1) and the switch 64, carried on the upper end of the frame assembly 23, is open. When said assembly moves forward toward the bags 22 on the

conveyor (dotted lines in FIG. 1) said switch 64 contacts the lead bag and is thereby closed to reverse the direction of arm travel and cause it to return to its original position again closing switch 63. If there are no bags present for contact by the switch 64, the frame assembly remains in position until a bag has advanced sufficiently to contact and close switch 64.

Now, when the frame assembly 23 reaches the bags on the conveyor, a normally open switch 66 firmly located near the bottom or pivoted end of the assembly 23, is closed by a cam 66a so as to actuate the fingers 36-37 and carry them into bag engaging position. When the frame assembly now moves away from the bags, the lead bag is carried therewith and delay action 15 of the cam 66a then releases the switch 66 to allow it to open. This causes the fingers 36-37 to release the bag for delivery to associated mechanism.

The embodiment shown in FIG. 8 is substantially like that previously described except that the bag grabber assembly 31a is designed to co-operate with shopping bags 71 of a type having a flap 72 on their bottom edge. In feeding the bags they are arranged on the conveyor assembly 12 substantially vertically, as before, but they are inverted so as to locate the bottom flap 72 on the upper end and on the side facing the grabber assembly. When in this position, their handles 73 are extended downwardly between the conveyor assembly chains.

The grabber assembly 31a is comprised of an arm 74 pivotally mounted between its ends, as at 75, to the top 30 of the frame assembly 23a, and it is connected to the base of the frame structure 11a, by a rod 41a so as to be tilted from a substantially horizontal retracted position, into a substantially vertical position when carried toward the bags. The arm 74 carries rigidly on its front 35 end a grabber element 76 having a resilient bag engaging finger 77 on its end. Thus, when the grabber assembly 31a is in bag engaging position and is then carried through an arc upwardly away from the supply of bags, the flap 72 on the lead bag is engaged by the finger 77 and said bag is carried upwardly into a substantially horizontal plane, as shown in dotted lines in FIG. 8, for engagement for example, by feed rollers 78 on an associated printing machine or other apparatus.

Although I have described preferred embodiments of my invention, in considerable detail, it will be understood that the description thereof is intended to be illustrative rather than restrictive, as details of the structure may be modified or changed without departing from the spirit or scope of the invention. Accordingly, I do not desire to be restricted to the exact construction shown and described.

I claim:

1. In bag handling equipment, the combination of, means for supporting and advancing a supply of bags in vertical position and each having at least one marginal flap facing the direction of advance, an upstanding frame structure mounted on a fixed horizontal axis, means to oscillatably rotate said frame structure toward and away from the lead bag, and at least one flap engaging element carried by said frame structure adapted when the frame structure is in one of its positions to engage behind said flap to carry the bag into a discharge position when the frame structure is moved into its other position, said flap engaging element comprising an assembly pivotally mounted at one end on said frame structure and having a flap engaging finger on its free end.

2. In the bag handling equipment recited in claim 1, wherein flaps are located on each side margin of the bags and the flap engaging elements are such as to positively engage behind both flaps.

3. In the bag handling equipment recited in claim 1, wherein the flap is on the top margin of the bag.

4. In the bag handling equipment recited in claim 1, wherein hydraulic means is provided to move the frame structure about its axis.

5. In the bag handling equipment recited in claim 1, wherein the bag flap engaging means comprises an articulated assembly including means to initially engage the lead bag to cause the flaps thereof to be extended out of the plane of the bag, and horizontally movable gripper elements adapted when in one of their positions to engage behind said flaps.

6. In the bag handling equipment recited in claim 1, wherein the flap engaging element includes an end ex-

tension disposed to bear against the lead bag to extend its flap, and the fingers are movable outwardly into engagement behind said flap.

7. In the bag handling equipment recited in claim 6, wherein hydraulic means is provided to actuate the flap engaging fingers.

8. In the bag handling equipment recited in claim 6, wherein electrically controlled hydraulic means is provided to actuate the frame structure and to actuate the flap engaging fingers.

9. In the bag handling equipment recited in claim 1, wherein there are two flaps on the bag and two flap engaging elements on the frame structure.

10. In the bag handling equipment recited in claim 1, wherein the flap engaging element includes means to initially bear against the lead bag to cause the flap thereof to be flexed out of the plane of the bag.
